UNITED STATES PATENT OFFICE.

JOHN H. CALDWELL, OF BASCO, ILLINOIS.

GATE.

SPECIFICATION forming part of Letters Patent No. 276,769, dated May 1, 1883.

Application filed January 16, 1883. (No model.)

To all whom it may concern:

Be it known that I, JOHN H. CALDWELL, a citizen of the United States, residing at Basco, in the county of Hancock and State of Illinois, have invented certain new and useful Improvements in Gates; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention in a perspective view. Fig. 2 shows a view of part of the invention, the gate and platform being in section across the line xx in Fig. 1. Fig. 3 is a vertical section taken on the line yy in Fig. 2.

This invention has relation to farm-gates; and it consists in the construction and novel arrangement of devices, as will be hereinafter fully described, and particularly pointed out in the claim.

Referring by letter to the accompanying drawings, a designates the slatted platform, bridge, or base, to which the gate-frame b , composed of end pieces, $c c$, and slats d , or slats d and rods e , as may be desired, is hinged, as shown, to one of its sills or side pieces, f . The side piece, f' , of the base a may be recessed vertically, as at g , to receive the free end of one of the battens or end pieces, c , where rods or barbed wire are used for the upper bars of the gate. Where the bars of the gate are composed entirely of slats this notch will not be necessary, as said bars will nearly fill the spaces between the slats of the base a .

It is probably not out of place to mention that the slats of the base a are nailed, spiked, or otherwise secured to sleepers h , embedded in the ground, to give stability to said base. The end pieces, $c c$, of the gate should pass down beside the sleepers h until the slats and rods of the gate rest upon the sleepers between the slats of the base when the gate is in a horizontal position or open, as shown.

At one end of the base a a post, i , is set into the ground, as shown, and is provided at its upper end with a cross-arm, j , at right angles to the line of the slats of the base and gate, which arm is suitably braced, as at $k k$. These

braces k are secured to opposite sides of the post i , and their upper ends are secured to opposite faces and near opposite ends of the cross-arm j . Levers l and l' are pivoted, one, l , to the face of the cross-arm j on the side nearest the gate, and the other, l' , to the brace k on the same side of the cross-arm. These levers $l l'$ are bifurcated at their inner ends, and in said bifurcations are pivoted the upper ends of metal straps, $m m'$, the former being shorter than the other. The lower end of the strap m is secured in a kerf, n , in the upper end of a nearly vertical bar, o , which carries on one of its edges the slotted latch-guard o' . The lower end of the strap m' is pivoted to the inner face of the bar o , as shown. The outer ends of the levers l and l' are provided with pendent rods $p p'$ at a distance from the gate to permit the team to approach and the driver to operate the levers to cause the gate to fall to a horizontal position without interfering with the animals' heads.

To the lower end of the bar o , on its inner face, is secured a metal plate, q , in an inclined position toward the top of the gate when the latter is in a horizontal position. This plate q is provided near its lower end with a slot, q' , through which a pin, r , extends into the hinge-slat of the gate. r' designates a latch for holding the gate in its vertical position, a stud, s , engaging the latch at this time. This latch is the ordinary weighted latch, its weighted end extending through the slot in the latch-guard o' , thereby causing it to be more effective in operation. $t t$ designate the hinges by which the gate is connected to the side piece of the base and the bottom slat of the gate.

The main object of this invention is to form a bridge or platform over which the vehicle or animal can pass when the gate is lowered. To lower the gate the levers (or one of them, which will operate the other) must be raised at their outer ends, which operation will release the catch by lowering the bar o , and the slotted plate q will move the top of the gate outward and downward to a point where its own gravity will assist it to its place in the slatted base a . The team and vehicle can then pass over, and the lever not previously grasped and raised may be now grasped and pulled down upon to raise the gate to its closed position.

Having thus fully described my invention, what I claim as new, and desire to secure by Letters Patent, is—

The combination, with a falling gate, of a slatted base, a post carrying pivoted levers, the inner ends of which are connected to a vertical bar by metal straps, and a slotted plate pivoted to the bar and connected to the gate by a

pin projecting from the hinge-slat, substantially as specified.

In testimony whereof I affix my signature in presence of two witnesses.

JOHN H. CALDWELL.
